UNITED STATES PATENT OFFICE.

HEINRICH WENZ, OF NEW YORK, N. Y.

PIPE-CLEANING ATTACHMENT.

SPECIFICATION forming part of Letters Patent No. 624,715, dated May 9, 1899.

Application filed July 29, 1898. Serial No. 687,190. (No model.)

To all whom it may concern:

Be it known that I, HEINRICH WENZ, of the city of New York, borough of Bronx, in the county of New York and State of New York, 5 have invented a new and Improved Pipe-Cleaning Attachment, of which the following is a full, clear, and exact description.

My invention relates to an attachment for pipes, intended to enable the interior thereof to be readily accessible for cleaning.

My invention comprises the novel features hereinafter described and claimed.

Reference is to be had to the accompanying drawings, forming a part of this specification, 15 in which similar characters of reference indicate corresponding parts in all the figures.

Figure 1 is an exterior view of a section of pipe, showing my device attached thereto, a portion of the cover-plate being broken away. 20 Fig. 2 is a longitudinal section of a section of pipe with my device attached, and Fig. 3 is a cross-section of the same.

It often happens that the pipes in houses which carry away wastewater become clogged, 25 and great difficulty is experienced in cleaning them by reason of the inability to get at the interior of the pipes.

The object of my invention is to supply an attachment for pipes of this character which 30 will make it possible to quickly get at the interior of the pipes and thoroughly clean them out. With this object the device is applied to pipes at the point where they are liable to become clogged.

35 The device consists of a frame C, which is secured to the pipe A by being soldered thereto or in any other suitable manner. This frame has a central opening which corresponds in size and location with an opening B in the 40 side of the pipe. This opening is preferably made much longer than its width, extending lengthwise the pipe. The frame C is provided with screw-holes F, as herein shown, one of these being placed at each end of the 45 opening. In making a device of this character to be applied to large pipes or where the pressure is great a larger number of screw-holes will be provided.

Secured to the outside of the frame C is a 50 cover-plate E, adapted to entirely cover the hole and to have a margin about the edge.

Between the cover-plate E and the frame C is placed a sheet of packing material D, which is of rubber, leather, or any suitable material. This cover-plate is secured to the frame 55 F by means of screws or bolts F', which pass through holes F in the ends of the cover-plate and enter the holes F in the frame C. This cover-plate and frame may be made flat, of thin brass or other material which may 60 be easily bent, and then bent to conform with any-sized pipe. This bending may be done in the process of manufacture or by the workmen when applying it to the pipe. By this means it is possible to obtain access to the interior of the pipe by removing the two screws 65 F' and the cover-plate held thereby. This gives an opening of suitable size in the pipe, and such as will permit the insertion of wires or other tools for cleaning out the pipes. 70

This device may be attached to the pipes at all places where they are liable to become clogged. Their use will render it unnecessary in many instances to call in the expensive services of a plumber when the pipes 75 have become clogged. They may be removed and replaced by any person.

This device is intended particularly for use in connection with lead pipe where, by reason of the soft and yielding material of which 80 the pipe is composed, it is very liable to become deformed about the edges of the opening by the tool used for cleaning it out. The previous attachment of the frame C, which would be made of brass, iron, or some metal 85 of greater strength than lead, stiffens and supports the edges of the openings and prevents deformation. By reason of the softness of lead it would be impossible to securely fasten the plate E directly to the pipe 90 by screws. The described construction prevents clogging of the pipe by the insertion of a plate or bar within the pipe and to which the outer plate may be secured.

Having thus fully described my invention, 95 I claim as new and desire to secure by Letters Patent—

1. A device for permitting access to the interior of pipes, comprising a frame or plate having a central hole and secured upon the exterior of the pipe, the pipe having a corresponding hole formed therein, and a cover-

plate secured to the frame by screws, substantially as described.

2. A device for permitting access to the interior of pipes, comprising a frame or plate having a central hole and secured to the exterior of the pipe, the pipe having a corresponding hole formed therein, a cover-plate

secured to the frame by screws, and a gasket or layer of packing material between the two, substantially as described.

HEINRICH WENZ.
